UNITED STATES PATENT OFFICE.

SEBASTIANO TOFANELLI, OF SAN FRANCISCO, CALIFORNIA.

PASTE DIE.

Application filed July 6, 1921. Serial No. 432,637.

To all whom it may concern:

Be it known that I, SEBASTIANO TOFANELLI, a citizen of the United States, residing at the city and county of San Francisco and State of California, have invented new and useful Improvements in Paste Dies, of which the following is a specification.

This invention relates to machinery for making paste products, such as macaroni, spaghetti, and the like, and particularly pertains to a die therefor.

In handling flour paste in the manufacture of macaroni and like products, the dies now in use readily clog and must be cleaned. In such a case, it is often necessary to remove the center pins from the dies and, as they are separately and rigidly held in position, it is quite a task to remove and replace all of such pins.

It is the principal object of the present invention to provide a die in which all of the pins forming the central openings through the products manufactured may be instantly removed and replaced, thus greatly facilitating the operation of the machine; and it is a further object of the present invention to provide a die which will form a product having a wall of uniform strength and thickness.

The present invention contemplates the use of a perforated disc through which flour paste may be pressed and which disc carries a secondary disc upon which core pins are mounted and supported in the center of the perforations of the main disc, said secondary disc and all its pins being capable of instant separation from the remainder of the die.

The invention is illustrated by way of example in the accompanying drawing in which—

Figure 1 is a central section through the die showing its construction and application;

Fig. 2 is a view in plan showing the face of the die.

Referring more particularly to the drawing, 10 indicates a base plate. This plate is formed with a plurality of openings 11. These openings have a cylindrical bore 12 at their lower ends while the remaining upper portion converges outwardly to form a frusto-conical section. The perforations 11 are distributed over the plate 10 of the die in any convenient manner. Secured to

the top face of the member 10 is a removable disc 13. This disc is secured to the plate by screws 14. As shown in Fig. 2, groups of small perforations 15 are formed through the disc. These groups of perforations occur along the circumferences of circles, the centers of which agree with the longitudinal centers of the passageways 11 in the main disc. Extending from the under faces of the removable disc 13 and from the centers of the groups of perforations 15 are core pins 16. These pins are of smaller outside diameter than the diameter of the cylindrical bores 12, the dimensions being sufficiently different to determine the thickness of the wall to be formed in the paste product pressed through the die. The upper ends of the pins are reduced in diameter so that the perforations 15 may be of a described size and may be satisfactorily arranged around the pins. Attention is particularly directed to the fact that the perforations 15 are distributed entirely around the pins, thus making it possible to uniformly supply paste to all sides of the opening and thereby insure that a product having a wall of uniform thickness will be provided. This is in contradistinction to the present common method of forming dies of this character in which the pins are supported from one side of the opening, thus preventing a uniform distribution of the paste and causing one wall of the product to be weak.

In the operation of the present invention the die is assembled as shown in the drawings, and may thereafter be suitably mounted at the end of a cylinder 17, this cylinder carrying piston 18 by which paste of a desired consistency may be forced through perforations 15 of the removable plate; from thence entirely around the pins 16 and filling the passageways 11, after which the paste will be forced out through the annular opening between the pin and circumscribed by the cylindrical bore 12, thus forming the paste product desired.

When it is necessary to clean the die, the screws 14 may be removed, after which the plates 10 and 13 are separated. When these plates are separated, all of the pins will of course be withdrawn from the passageways 11. Each part of the die may then be thoroughly cleaned and re-assembled. If it is necessary to remove or replace individual pins this may be readily done.

It will thus be seen that a die here disclosed insures that paste products having walls of uniform strength and thickness may be made, and when it is desired the die may be readily cleaned and replaced.

While I have described the preferred form of my invention, it is to be understood that various changes may be made by those skilled in the art without departing from the spirit of the invention.

Having thus described my invention, what I claim and desire to secure by Letters Patent is:

1. A paste forming die comprising a body plate having a plurality of passageways formed therethrough, a pin extending into each of said passageways, said pin being of a diameter to create an annular opening between its outer circumference and the inner circumference of the passageways, and a removable plate disposed above the body plate and carrying all of said pins and supporting them in their proper positions, said removable plate being formed with a plurality of groups of perforations, the perforations of each group being arranged about the vertical axis of the said passageways and within the boundary thereof.

2. A paste forming die comprising a body plate having a plurality of passageways formed therethrough, a removable plate mounted on the upper surface of said body plate, a plurality of downwardly extending pins carried by the removable plate, said pins having a reduced upper end, an enlarged lower end, and a conical intermediate portion, the reduced end of said pins being secured in the removable plate, said pins extending one into each of said passageways, wherein they are centrally located and of a diameter so as to create an annular opening between their outer circumference and the inner circumference of the passageways, said removable plate being formed with a plurality of groups of perforations which are arranged in a circle about said pins and within the boundary of said passageways.

3. A die for forming macaroni and the like, comprising a body plate having a plurality of cylindrical openings passing part

way through the plate, said openings communicating with the smaller ends of frusto-conical passageways; a removable plate secured to said body plate in intimate contact therewith and disposed over the large ends of said frusto-conical passageways, said plate being formed with groups of perforations arranged in spaced relation to each other around the longitudinal axis of said passageways; and pins carried by the removable plate, one of said pins being located at the central axis of each passageway and extending therethrough.

4. A paste forming die comprising a body plate having a plurality of frusto-conical recesses formed therein and disposed with their larger ends at the upper surface of said plate, the smaller ends of said recesses communicating with cylindrical openings, a removable plate removably secured to said body plate in intimate contact with the upper surface thereof, said removable plate being formed with groups of perforations arranged in spaced relation to each other around the longitudinal axis and within the boundary of said frusto-conical recesses, and downwardly extending pins carried by said removable plate and located concentrically with the said frusto-conical recesses and cylindrical openings.

5. A paste forming die comprising a body plate having a plurality of frusto-conical passageways formed therein and disposed with their larger ends at the upper surface of said plate, the smaller ends of said openings terminating in cylindrical openings, a removable plate removably secured to said body plate in intimate contact with the upper surface thereof, a plurality of downwardly extending pins carried by said removable plate and located one at the central axis of each of said passageways, said pins having reduced upper ends secured in said removable plate, the other end being disposed in said passageways, said removable plate having groups of perforations formed therein, arranged in spaced relation in a circle about said pin and within the boundary of said passageways.

SEBASTIANO TOFANELLI.
